UNITED STATES PATENT OFFICE.

OTTO JOHNE, OF BAUTZEN, GERMANY, ASSIGNOR TO FIRM OF BAUTZNER INDUSTRIEWERK, AKTIENGESELLSCHAFT, OF BAUTZEN, GERMANY.

MACHINE FOR CUTTING PILES OF PAPER.

1,143,765.

Specification of Letters Patent.

Patented June 22, 1915.

Application filed January 8, 1914. Serial No. 811,045.

To all whom it may concern:

Be it known that I, OTTO JOHNE, engineer, a subject or citizen of the German Empire, residing at Bautzen, Germany, have invented certain new and useful Improvements in Machines for Cutting Piles of Paper and the like, of which the following is a specification.

This invention consists of an improvement 10 in the machine described in the specification filed with my application for Letters Patent Serial No. 762657 of April 21, 1913, and more particularly in the modification described in my subsequent specification Serial 15 No. 811,044 in which the clamp springs are connected at one end with a fixed pivot and at the other end with a lever which is itself connected with a toggle joint. This toggle joint is operated by a crank gear and its 20 other free end is connected with the levers serving to actuate the press beam. In practice this arrangement is found to be complicated owing to the employment of the toggle joint. The spring pressure is transmitted to 25 the press beam by the intermediary of a large number of levers and the toggle joint, whereby useless work is performed. This driving mechanism can be greatly simplified 30 by dispensing with the toggle joint and interposing an appropriate form of springs between the crank gear and the lever mechanism for operating the press beam.

Now the present invention resides in arranging the press springs between two levers oscillating in stationary bearings, one of these levers being moved by the crank gear, while the other transmits to the press beam either directly or by the intermediary 40 of levers the movement imparted to it and the spring pressure exerted upon it.

An embodiment of the said machine is illustrated in the accompanying drawings, in which—

Figure 1 shows the machine in front elevation, and Fig. 2 is a cross section thereof.

The machine is driven in the known manner off the pinion 14 onto the intermediate wheel 15. The pinion 16 is mounted upon the same shaft and meshes with the eccentric wheel 18 mounted on the shaft 17. Upon the other end of the shaft 17 the eccentric disk 19 is mounted and the tension rods 21 for the knife beams 22 engage the studs 20 on this disk in the known manner. The 55 shaft 17 also carries the wheel 23 which

meshes with the wheel 24 mounted on the crank shaft 13.

The connecting rod 12 connects the crank 13 with the oscillating lever 10 which rotates freely on the shaft 11. The lever 7 is connected with the lever 10 by means of one or more springs 9. The bell crank lever 5 is also freely rotatable upon the shaft 11 and the bell crank lever 4 and the lever 7 are firmly keyed upon the shaft 8. By means 60 of the tension rod 6 the bell crank levers 4 and 5 are connected one with the other and by means of the links 3 and the tension rods 2 they are connected with the press beam 1.

The clamping device acts in the following 65 manner: The crank 13 is rotated by the wheel 24 and by means of the connecting rod 12 imparts a reciprocating movement to the levers 7 and 10 and consequently to the spring 9 also. The bell crank lever 5 and 70 the bell crank lever 4, which transmits its movement to the bell crank lever 5 through the tension rod 6 (both these bell crank levers being connected with the press beam 1 by means of the link 3 and tension rods 2) 75 impart a vertical reciprocating movement to the beam 1. If a pile of paper is situated beneath it the beam will bear upon it and as a result the rods 2, the links 3, the bell crank levers 4 and 5 and the lever 7 are incapable 80 of further displacement so that the cranks 13 are only able to compress the springs 9 by means of the connecting rod 12 and the lever 10, the pressure of these springs being 85 then transmitted to the press beam. 90

The crank positions for the knife beam 22 and press beam 1 are the same as described in my prior specification Serial No. 762657, of April 21, 1913. When the machine is started first of all the compression takes 95 place and then after the spring is compressed, the pile of paper is cut through.

By introducing slight modification the compression springs 9 can be replaced by 100 tension springs.

In the embodiment of the invention here described the reciprocating movement of the spring casing 9 and its spring pressure are transmitted to the lever 7, which oscillates about the shaft 8 and simultaneously displaces the bell crank lever 4 and with it the bell crank lever 5. By means of special connecting rods 3 and tension rods 2 these two bell crank levers operate the press beam 1. 105 The oscillating lever 7 can, however, also be 110

constructed in such a manner that it will act directly upon the tension rods 2, similarly the oscillating levers 4 and 5 can be replaced by lever mechanisms of different construction.

Having now particularly described and ascertained the nature of my said invention and in what manner the same is to be performed, I declare that what I claim is:

19. In paper cutting machines of the character described, in combination with the cutter thereof, an automatic spring actuated paper presser, two levers between the springs of said presser, stationary bearings in which

said levers oscillate, a crank gear for operating one of said levers and a system of levers connected to the other of said levers for imparting to the beam of the presser a reciprocating vertical movement and compressing the paper, substantially as described.

In testimony whereof I have hereunto set my hand in presence of two subscribing witnesses.

OTTO JOHNE.

Witnesses:

PAUL ARRAS,
OTTO MEDAM.
